UNITED STATES PATENT OFFICE.

RUDOLPH HOFFMAN, OF KANKAKEE, ILLINOIS, ASSIGNOR TO SEARS, ROEBUCK AND COMPANY, OF CHICAGO, ILLINOIS, A CORPORATION OF NEW YORK.

OIL-STOVE.

1,345,775.

Specification of Letters Patent.

Patented July 6, 1920.

Application filed May 3, 1917. Serial No. 166,084.

To all whom it may concern:

Be it known that I, RUDOLPH HOFFMAN, a citizen of the United States, residing at Kankakee, in the county of Kankakee and State of Illinois, have invented certain new and useful Improvements in Oil-Stoves, of which the following is a specification.

The burners of oil stoves are provided with chimneys for directing the current of heated air and products of combustion toward a utensil to be heated, and in order to reduce the radiation of heat from the chimney, a drum may be employed, which surrounds the chimney and is secured thereto. The chimney and drum thus provided are supported upon the burner so as to be capable of being tilted thereon, in order to permit of access to the burner for lighting or other purposes, and it will be apparent that in order to permit of such tilting movement of the chimney and drum, it is essential that they terminate at their upper ends a material distance below the grate upon which is supported the utensil to be heated. Accordingly, much heat is permitted to escape from the upper end of the chimney and drum without doing any appreciable amount of useful work. The object of the present invention therefore is to minimize such radiation and insure that as much as possible of the heat generated by the burner shall be applied to useful work.

In the drawings, Figure 1 is a fragmental vertical sectional view of an oil stove embodying the features of my invention. Fig. 2 is a fragmental front elevation. Fig. 3 is a sectional view taken in the plane of line 3—3 of Fig. 1. Fig. 4 is a section on line 4—4 of Fig. 1.

In the drawings, 1 denotes a blue-flame wick oil burner of any suitable type. 2 is a chimney of any ordinary or desired form resting upon an annular shoulder 3 upon the burner. 4 is a stove top provided with the usual grate 4^a to support the utensil or other article to be heated. The chimney 2 extends relatively near the stove top 4 so as to conduct the heated air and combustion products close to the bottom of the vessel to be heated.

To minimize the radiation of heat from the chimney 2, I surround the chimney with a drum 5. The chimney and the drum may be connected together in any suitable man-

ner. In the present embodiment they are united at their lower ends by electric spot welds.

The chimney 2 is shown as being upwardly tapered, so as to provide an annular space 6 between the chimney and the drum. To provide for the entrance of air to the space 6 a suitable number of openings 7 are formed in the lower portion of the drum.

A handle 8 of any preferred construction is attached to the drum. Herein the handle is shown as secured in place by bolts 9 and 10 extending through the drum and the chimney. 11 is a spacer on the bolt 9 between the chimney and the drum.

The drum 5 comprises a lower or main section 5^a of about the same length as the chimney 2, and an upper section 5^b surrounding the main portion of the drum and movably supported thereon in any suitable way. Herein are shown three equidistant pins 13 set in the main portion of the drum and extending into upwardly inclined slots 14 in the section 5^b. 15 is a handle by means of which the section 5^b may be turned to the extent limited by the length of the slots 14. As the section 5^b is turned it rises or descends, depending upon the direction of turning movement. Any suitable means may be used to retain the section 5^b in adjusted position, as, for example, notches 16 in the upper wall of one of the slots 14, the pin 13 entering any of said notches.

It will be apparent that when the upper section 5^b is in its lowermost position the drum may be readily tilted to permit of access to the burner, for lighting or other purposes, but when in its most elevated position, the section 5^b is preferably in contact with or very close to the lower side of the grate 4^a, so that it is prevented by the grate from being tilted. To insure sufficient means of escape for the heated air and products of combustion, the upper portion of the section 5^b is preferably provided with a series of perforations 17.

Preferably registering windows 18 are provided in the chimney and the drum, near the lower ends thereof.

In use, the hot gases are directed to the grate 4^a by the chimney 2. The heat radiated from the chimney warms the air in the space 6, and causes an upward current of air in said space, said heated current

being discharged close to the utensil being heated. The comparatively cool air drawn in through the openings 7 prevents overheating of the burner and the lower part 5 of the chimney. When the burner is to be lighted, the section 5^b is lowered, and the drum and the chimney tilted by means of the handle 8 to allow access to the wick. After the burner has been lighted, the section 10 5^b is elevated so as to direct the heated gases close to the bottom of the utensil to be heated.

I claim as my invention:

- 15 1. In an oil stove, the combination with a fixed top having a grate, and a burner stationarily supported below the grate, of a unitary heat-conducting device carried solely by the burner and comprising a chimney, a drum surrounding the chimney so as 20 to provide an annular air space between the chimney and drum, the lower ends of said chimney and drum being rigidly secured together and there being air inlet openings communicating with the lower part of said 25 space, said chimney and drum being mounted to tilt upwardly about a pivot point near their lower edges so as to provide a space to give access to the burner, and a tubular upper section freely movable relative to the upper 30 per end of the drum and adapted to be sup-

ported thereby either in a lowered position such as to permit of a tilting of the device upon its support unrestrained by the grate or in operative position immediately adjacent the underside of the grate.

85

2. In an oil stove including a fixed grate and a burner stationarily supported below the grate, a drum supported upon the burner so as to be tiltable thereon and comprising a lower section, an upper section, 40 and means for supporting the upper section upon the lower section either in position with its upper end terminating a sufficient distance below the grate to permit the drum to be tilted, or in position with its upper end near or in contact with the grate to prevent the free escape of heat between the drum and grate, said means being adapted to permit the free movement of the upper section relative to the lower section from 45 one of said positions to the other and comprising a pin mounted upon one section, there being an inclined slot in the other section having a notch at one end for receiving the pin whereby to prevent the pin 50 from sliding in one direction in the slot.

55

In testimony whereof I have hereunto set my hand.

RUDOLPH HOFFMAN.
